United States Patent Office

Des. 195,397

Patented June 11, 1963

195,397

TOILET SEAT COVER

Patricia Toole Whitehorn, Golden Acres,
Whitehorn Farms, Floweree, Mont.

Filed Sept. 25, 1961, Ser. No. 66,828

Term of patent 7 years

(Cl. D4—5)

FIG. 1

FIG. 2

FIG. 1 is a perspective view of a toilet seat cover showing my new design; and

FIG. 2 is a bottom plan view thereof taken on a reduced scale.

The broken lines are shown for illustrative purposes only.

I claim:

The ornamental design for a toilet seat cover, as shown and described.
